DRAFTING IMPLEMENT

Edgar E. Kellems, Pasadena, Calif.

Application March 3, 1948, Serial No. 12,790

2 Claims. (CL 33—104)

1

The present invention relates to drafting implements.

One object of my invention is to combine several drafting implements into one convenient device.

Another object of my invention is to combine all of the usual drafting angles into one device so that each angle and the device is simple to use.

A further object of my invention is to provide an expanded scale protractor that is extremely accurate in use.

A still further object of my invention is to attain the objects and advantages above enumerated in a one-piece implement.

Other objects and advantages will become apparent in reference to the following specification and attached drawings, in which

Fig. 1 is a plan view of my invention;

Fig. 2 is a plan view of the invention showing the use in one position;

Fig. 3 is a plan view of the invention showing the use in another position, and

Fig. 4 is a plan view of the invention showing the use of the protractor.

In the following detailed description of the invention like numerals indicate like parts in the several figures of the drawings. The reference numeral 10 indicates generally the invention which comprises a one-piece transparent plastic drafting implement having a base portion 11 and an upstanding portion 12. The base portion 11 has a base edge 13 and an upper edge 14 parallel to the base edge 13. The upstanding portion 12 has an inner edge 15 perpendicularly extending from the upper edge 14 of the base portion 11. An outer edge 16 of the upstanding portion 12 joins the inner edge 15 to form an included angle of 30 degrees. A lower edge 17 of the upstanding portion 12 joins at one end with the outer edge 16 to form an included angle of 105 degrees and at its other end joins with the base edge 13 of the base portion 11 to form an included angle of 135 degrees.

The upper edge 14 of the base portion 11 is provided with an imprinted measuring scale having its zero point a fraction removed from the inner edge 15 of the upstanding portion 12. This location of the zero point permits direct measuring and drawing without moving the implement 10. The inner edge 15 of the upstanding portion 12 is likewise provided with a scale with its zero point a fraction removed from the upper edge 14 of the base portion 11. The outer edge 16 of the upstanding portion 12 is also provided

with a scale. Each of the aforementioned scales is marked and numbered in the conventional manner.

A protractor arc is provided on the upstanding portion 12 having as its center the point on the upper edge 14 of the base portion 11 indicated by the numeral line extending from the C and arrow imprinted on the implement. The protractor scale is numbered for unidirectional use.

In Figures 1, 2 and 3 of the drawings, a portion of a standard T square is indicated as 18.

In Figure 4 of the drawings, a base line, from which a specific angle is to be drawn, is indicated by a dash line extending across the figure. It is to be noted that if desired a slight modification of the basic invention may be made by cutting off the tip of the upstanding portion 12 along the dotted line extending from the five units mark on the inner edge and outer edge squares. It should be clear that modifications may be resorted to in the scales without departing from the basic invention.

In the use and operation of the invention for drawing a line at an angle to the horizontal, the use of the lower edge 13 of the base portion 11 as a base edge will be first discussed. With the lower edge 13 forming the horizontal, the inner edge 15 will be at 90 degrees to the horizontal, the outer edge 16 will be at 60 degrees to the horizontal, and the lower edge 17 will be at 135 degrees to the horizontal. It is to be noted that angles of 45 degrees and 120 degrees may be drawn by turning the implement with the scale face down using the same base edge 13.

By using the lower edge 17 as the horizontal, the upper and lower edges 14 and 13 of the base portion 11 will be at 45 degrees to the horizontal, the inner edge 15 will be at 135 degrees to the horizontal and the outer edge 16 will be 105 degrees to the horizontal. An angle of 75 degrees may be made by turning the implement face down using the lower edge 17 as the base and outer edge 16 as the drawing edge.

By using the outer edge 16 as the horizontal, the upper and lower edges 14 and 13 of the base portion 11 will be at 120 degrees to the horizontal, the inner edge 15 will be at 30 degrees to the horizontal and the lower edge 17 will be at 75 degrees to the horizontal. By reversing the implement with the face down using outer edge 16 as the base angles of 60 degrees, 105 degrees and 150 degrees may be formed. As indicated above, the following angles may be directly drawn by using a combination of one base

edge and one drawing edge: 30 degrees, 45 degrees, 60 degrees, 75 degrees, 90 degrees, 105 degrees, 120 degrees, 135 degrees and 150 degrees, or, in other words, any angle possible through the normal use of the 30-60-90 triangle and the 45 triangle or any combination thereof.

The protractor is used in the following manner: to measure an angle formed by two lines, the upper edge 14 of the base portion 11 is laid along one of the lines with the apex of the two lines falling at the point marked with an arrow and C the angle between the lines may then be read directly from the point of crossing of the second line with the protractor scale.

In drawing a line at a specific angle to the horizontal, the protractor scale and the point marked with an arrow and C are lined up on the angle desired with a horizontal base line, the upper or lower edges 14 or 13 may then be used to directly draw the angle desired.

Having thus described my invention in detail, my invention is delineated by the following claims.

I claim:

1. A drafting implement, involving: a flat member of generally L form having three external edges, there being a first and a second external edge at 60° internal angle to each other and a third intervening edge at 45° external angle to said first edge and 75° external angle to said second edge, there also being two perpendicularly related internal edges, one thereof being parallel to said first edge and the other converging at 30° included angle relative to said second edge.

2. A drafting implement, involving: a flat

member of generally L form having a parallel edge leg and a converging edge leg, the internal edges of said legs being mutually perpendicular and the external edges being acutely related, the apex of said external edges being truncated to form a third external edge, whereby any of said external edges may be placed against a straight edge to dispose said internal edges in any of three different angular positions, said converging edge leg defining a 30° included angle, and said third external edge being disposed at 45° external angle to one of said external edges and 75° external angle to the other of said external edges whereby a line drawn normal to at least two of said external edges may pass through the point of intersection of said internal edges.

EDGAR E. KELLEMS.
